UNITED STATES PATENT OFFICE

2,472,256

VOLTAGE STABILIZER

Gerrit Mak, Hendon, South Australia, Australia,
assignor to Hartford National Bank & Trust
Company, Hartford, Conn., as trustee

Application January 10, 1948, Serial No. 1,589
In Australia September 11, 1945

Section 1, Public Law 690, August 8, 1946
Patent expires September 11, 1965

6 Claims. (Cl. 323—63)

1

The present invention relates to voltage stabilizers.

It is well known that voltages and currents may be stabilized by a bridge or the like device having incandescent lamps included in one or more of its arms. Ballast resistors in which the resistance varies with changes in the temperature of the resistor may also be used for the same purpose.

Bridges and ballast resistors suffer from the defect that their action is not instantaneous as a time interval occurs after a change in voltage before the device accommodates itself to the new conditions and stabilizes the voltage. For this reason bridges and ballast resistors cannot be utilized to eliminate voltage or current variations which have a time period less than this time interval.

It is the primary object of this invention to provide means for reducing rapid variations in the output voltage from voltage stabilizing devices such as bridges, ballast resistors or the like.

According to the present invention a circuit having a sufficiently high Q factor to provide a substantial impedance to voltage variations which have a time period less than a predetermined value, is operatively associated with the voltage stabilizer.

In order that the invention may be more readily understood reference will now be made to the accompanying drawings in which:

Figure 1 is the circuit diagram of a well-known voltage stabilizer:

Figure 2 shows graphs illustrating variations in the input voltage and the resultant change in output voltage of the stabilizer of Figure 1:

Figure 3 is the circuit diagram of one embodiment of the invention:

Figure 4 is a graph illustrating the form of the output voltage of the stabilizer of Figure 3 when a variation occurs in the input voltage applied thereto: and

Figure 5 is the circuit diagram of an alternative form of the invention.

Referring to Figure 1, the arms 5, 6, 7 and 8 form a bridge network having input terminals 1 and 2 and output terminals 3 and 4. The arm 5 of the bridge network includes a resistor of the type wherein variations in the current flowing therethrough cause variations in temperature which, in turn, varies the resistance of the resistor. A lamp filament constitutes a resistor of this type. The remaining arms 6, 7 and 8 are composed of resistors of normal type.

If the resistors constituting the bridge net-

2

work are properly chosen, the network tends to maintain a substantially constant output voltage at the terminals 3 and 4, irrespective of variations in the input voltage applied to the terminals 1 and 2.

A stabilizer of the type shown in Figure 1 suffers from the defect that its action is not instantaneous as time is required for any increase or decrease in current flowing through the arm 5 to affect the temperature of this arm so as to change its resistance. This defect is graphically shown in Figure 2 in which the graph (a) represents an input voltage which suddenly increases in value and the graph (b) represents the output voltage which also suddenly rises in value and then slowly decreases to its original value.

According to the invention a circuit such as a low pass filter or a circuit tuned to the frequency of the input voltage is interposed between the bridge network and the output terminals. This is shown in Figure 3 of the drawings where the reference numeral 9 indicates such a circuit. The circuit should have a relatively high Q factor so that it presents a relatively high impedance to rapid fluctuations in voltage.

Figure 4 graphically shows the nature of the output voltage from the circuit of the invention when the input voltage increases as shown in Figure 2. The magnitude of the fluctuation is reduced and the increase in voltage is more gradual. The higher the Q factor of the circuit 9 the more effective is the stabilizing action.

A further embodiment of the invention is shown in Figure 5 wherein a very selective tuned valve amplifier is used instead of the circuit 9 of Figure 3. In Figure 5 the frequency selecting circuit comprises a Wien bridge formed by the resistors 10, 11 and 12 and the capacitors 13, 14 and 15. With this arrangement an output voltage similar to that graphically shown in Figure 4 is obtained, when the output voltage varies as illustrated in Figure 2.

Having now described my invention, what I claim as new and desire to secure by Letters Patent is:

1. A voltage stabilizing system comprising a network including a ballast resistance, input means to apply an alternating voltage of predetermined frequency to said network, the amplitude of said alternating voltage being subject to fluctuations, output means to derive said alternating voltage from said network whereby said voltage is stabilized by said ballast resistance for relatively slow fluctuations in amplitude, and an impedance circuit interposed between said net-

work and said output means, said circuit having a characteristic presenting a relatively high impedance to amplitude fluctuations having a time period less than the time period of said predetermined frequency and a negligible impedance to voltage of the time period of said predetermined frequency.

2. A voltage stabilizing system comprising a network including a ballast resistance, input means to apply an alternating voltage of predetermined frequency to said network, the amplitude of said alternating voltage being subject to fluctuations, output means to derive said alternating voltage from said network whereby said voltage is stabilized by said ballast resistance for relatively slow fluctuations in amplitude, and a low pass filter interposed between said network and said output means, said filter having a band pass characteristic accommodating said predetermined frequency and discriminating against amplitude fluctuations having a time period less than the time period of said predetermined frequency.

3. A voltage stabilizing system comprising a network including a ballast resistance, input means to apply an alternating voltage of predetermined frequency to said network, the amplitude of said alternating voltage being subject to fluctuations, output means to derive said alternating voltage from said network whereby said voltage is stabilized by said ballast resistance for relatively slow fluctuations in amplitude, and a series resonant circuit interposed between said network and said output means and tuned to said predetermined frequency whereby said circuit presents a relatively high impedance to amplitude fluctuations having a time period less than that of said predetermined frequency and a negligible impedance to voltage of the time period of said predetermined frequency.

4. A voltage stabilizing system comprising a network including a ballast resistance, input means to apply an alternating voltage of predetermined frequency to said network, the amplitude of said alternating voltage being subject to fluctuations, output means to derive said alternating voltage from said network whereby said voltage is stabilized by said ballast resistance for relatively slow fluctuations in amplitude, and a selective electron discharge tube amplifier inter-

posed between said network and said output means and tuned to said predetermined frequency whereby amplitude fluctuations having a time period less than that of said predetermined frequency are attenuated by said amplifier.

5. A voltage stabilizing system comprising a four arm resistance bridge one arm of which is constituted by a ballast resistance, input means to apply an alternating voltage of predetermined frequency across one pair of opposing diagonals in said bridge, said alternating voltage being subject to amplitude fluctuations, output means to derive said alternating voltage from the other pair of opposing diagonals to said bridge whereby said voltage is stabilized for relatively slow fluctuations in amplitude, and an impedance circuit interposed between said bridge and said output means, said circuit presenting a relatively high impedance to amplitude fluctuations of voltage having a time period less than the time period of said predetermined frequency and a negligible impedance to voltage of the time period of said predetermined frequency.

6. A voltage stabilizing system comprising a four arm resistance bridge one arm of which is constituted by a ballast resistance, input means to apply an alternating voltage of predetermined frequency across one pair of opposing diagonals in said bridge, said alternating voltage being subject to amplitude fluctuations, output means to derive said alternating voltage from the other pair of opposing diagonals to said bridge whereby said voltage is stabilized for relatively slow fluctuations in amplitude, and a selective electron discharge tube amplifier interposed between said network and said output means and tuned to said predetermined frequency whereby amplitude fluctuations having a time period less than that of said predetermined frequency are attenuated by said amplifier.
